UNITED STATES PATENT OFFICE.

CLARENCE R. MAXWELL, OF LOS ANGELES, CALIFORNIA.

ELECTRIC METALLIC WINDOW-CURTAIN.

1,374,670.

Specification of Letters Patent.

Patented Apr. 12, 1921.

Application filed August 30, 1920. Serial No. 407,005.

To all whom it may concern:

Be it known that I, CLARENCE R. MAXWELL, a citizen of the United States, residing in the city and county of Los Angeles and State of California, have invented a new and useful Electric Metallic Window-Curtain, of which the following is a specification.

This invention relates to certain novel and useful improvements in window curtains, and has for its objects to provide a curtain which may be electrically charged for and as an anti-burglar device, which may be de-energized for operating the curtain, and which, when, energized, is also locked against operative movement.

Other objects are to provide improved means for operating the roller to wind up the curtain, and improved means for releasing the curtain catch whereby the same will be automatically wound upon the roller.

A further object is to provide mechanism whereby the curtain will remain charged or energized in its various positions of adjustment relative to the window.

A further object of the invention is to provide a curtain either manually controlled or electrically controlled, the mechanism in each instance, being subject to the control of a manually operated electric switch, placed in such a position that it cannot be readily tampered with by a person on the outside of the window, and placed so as not to be tampered with by children.

The several features of my invention and the various advantages resulting from their use conjointly or otherwise will be apparent from the following description and appended claims.

It is also my purpose to provide a device of the type set forth which will embrace the desired features of simplicity, efficiency and durability, which will operate effectively for its intended purpose, and wherein the component parts will be so arranged that the possibility of derangement is reduced to a minimum, and, while the drawings, illustrate a preferred embodiment of the invention, it is to be understood that changes, alterations and modifications, falling within the scope of the claims, may be resorted to if desired.

Upon the annexed drawings, Figure 1 is a perspective view of a window, with my improved curtain applied thereto. Fig. 2 is a top and sectional plan view of the cur-

tain, showing the roller therefor in section. Fig. 3 is an end view of the curtain and hanger. Fig. 4 is a perspective and fragmentary view of the curtain roller, showing the two half sections thereof clamped together with screws. Fig. 5 is a transverse sectional view of the curtain roller. Fig. 6 is a transverse sectional view showing the curtain roller within the housing, and the spring for operating the curtain roller. Fig. 7 is a fragmentary detail view showing the method of insulating the curtain release catches. Fig. 8 is a fragmentary and detail view of the curtain fabric, showing the arrangement of contact elements thereon. Fig. 9 is an end elevation of the window curtain and hanger, showing the electric locking mechanism which is operative when the curtain is energized. Fig. 10 is a fragmentary and detail view showing an electric locking mechanism for the release catches, effective when the curtain is energized. Fig. 11 is a diagrammatic view of the electric elements and method of wiring the device. Fig. 12 is a transverse sectional view of the curtain roller, showing a commutation ring and contact brushes. Figs. 13 and 14 are sectional detail views of the notched curtain retaining racks.

Referring to the drawings, my improved curtain consists of a roller housing 21, provided with end brackets 22, and a longitudinal bottom opening 23. The housing is constructed preferably of porcelain, but any suitable insulating material may be used. A roller 24 is journaled in the brackets 22, and consists of two substantially, semi-cylindrical parts, 25 and 26, secured together at the ends by screws 27. The part 25, has the integral shafts 28 and 29. The shaft 28 is rotatively mounted on a tubular projection 30, fixed to the housing. The shaft 29 is provided with a ratchet wheel 31. Spiral springs 32 and 33 have their inner ends secured to the shafts 28 and 29, and their outer ends secured to pins 34, projecting from the housing. As the curtain 35 is pulled downward, the spiral springs contract, and when the curtain is released, the spiral springs tend to return to their normal position, thereby winding the curtain on the roller. The roller, constructed preferably of porcelain, has a hollow bore 36, lined with contact rings 37, which alternate with insulating ring members 38. The curtain 35 is constructed preferably of asbestos fab-

ric, and has arranged on the outer side 39, a series of strips 40, consisting of copper wire woven into a fabric. Alternate strips of the wire fabric, are arranged to be energized from an electric conduit. The non-rotative tubular projection 30, has connected thereto, the metal conductors 41, which are connected at the opposite end to a non-conductive trunnion member 42, journaled in the roller member 25. The conductors 41, are provided with a series of brushes 43, so arranged that the brushes on one of members 41 are in contact with a series of the rings 37, and the brushes of the opposite conductor are in contact with an alternating series of the rings 37. The strips 40, on the curtain, are therefore charged alternately, with current of opposite polarity.

20 The metal conductors 41, are connected to electric conduit terminals 44, which pass out through the tubular projection 30, and to the electric switch 45, located upon the window casing 46, so as to be out of reach of children, and serving to connect the terminal conduits 44 with an electric circuit indicated by the wires 47.

The bottom or free end of the curtain is provided with a non-conductive tubular portion 48, within which is mounted the shafts 49, terminating at their outer extremities in catches 50, adapted to engage with notched members 51. These notched members are mounted in non-conductive channels 52, preferably constructed of porcelain. The inner extremities 53, of shafts 49, are provided with non-conductive covers 54, angularly disposed to serve as handles for operating the plungers 50 and shafts 49, 40 against the tension of spring 55, to release the curtain.

That the curtain may, when pulled downward, be locked in position when energized by the electric current, I have provided magnetic coils 56, connected in series, and connected to certain of the metal fabric conductive strips, whereby a portion of the current is shunted through the magnetic coils 56. The shafts 49, are thus magnetically energized, as are the catches 57, which engage with the slots 58, in the shafts 49. When thus energized, the catches 50 cannot be released by pressing upon the handles 54.

An additional means for locking the curtain in position when energized, consists of ratchet pawl 59, engaging with the ratchet wheel 31. The pawl 59 has an integral sleeve 60, rotatively mounted on a stud 61, projecting from the housing, and is further provided with a lever arm 62, to which is attached a cord 63, provided with a handle 64. A spring 65, coiled around the sleeve 60, and having one extremity 66, in engagement with the lever arm 62, and the opposite extremity in engagement with the hous-

ing, serves to maintain the pawl 59 in engagement with the ratchet wheel 31.

To release the curtain, the handles 44, must be pressed together to release the catches 50, and at the same time the cord 63 70 must be pulled downward to release the pawl 59, whereupon springs 32 and 33 will operate the roller to wind the curtain thereon.

To lock the pawl 59 in operative engagement with ratchet wheel 31, I have provided a solenoid 67, which is energized on closing the switch 45, and a plunger 68, operating in the solenoid, and engaging in its uppermost position, with a projection 69, on pawl 80 63. With this device, the switch 45 must first be turned to open the circuit and de-energize the solenoid, before the pawl can be released from engagement with wheel 31.

From the foregoing description, taken in connection with the drawings, it may be seen that I have provided an efficient anti-burglar curtain, constructed entirely of fire-proof material, capable of being electrically charged and energized so that a burglar would on attempting to enter a window, be repelled by the curtain, and capable of being locked in any adjusted position, whereby the curtain could be left at a position for ventilation, and at the same time, not readily tampered with for entrance at the window.

It is apparent that, should one of the locking means become ineffective, as for instance, the locking means for catches 50, the remaining locking means will still be effective, 100 until the switch 45 is turned to open the electric circuit. For convenience of illustration, the switch 45 is shown mounted on the window casing, but in actual practice, the switch may be located in any preferred position.

What is claimed is:

1. In a fireproof window curtain, the combination with a porcelain housing and hangers, of a shade roller journaled in the 110 hangers, and an asbestos curtain fixed to the roller.

2. The combination with a housing and brackets integral therewith of a roller journaled therein, a non-conductive curtain fabric fixed to the roller, strips of conductive material fixed to the non-conductive fabric, means for energizing the same, and means for locking the curtain in any adjusted position.

3. The combination with a curtain housing, of a roller rotatively mounted therein, a non-conductive curtain attached thereto, metallic fabric strips mounted thereon, means for energizing the metallic fabric 125 strips, springs having their inner extremities fixed to the roller and their outer extremities fixed to the housing, said springs being tensed as the curtain is drawn downward, means for securing the curtain in any 130

adjusted position, means for locking the securing means, electro-magnetic means for actuating the locking means, and means for energizing the electro-magnetic means.

- 5 4. The combination with a curtain housing, of a roller mounted therein, a curtain attached to the roller, fabric strips of conductive material affixed to one side of the curtain, means for energizing the fabric 70 strips, notched bars affixed to the window casing, latches mounted in the free extremity of the curtain, and adapted to engage with the notched bars, a spring interposed between the inner ends of the latches and 75 10 normally holding the latches in engagement with the notched bars, said latches having notches therein, a non-conductive tubular casing in the curtain extremity, said latches being slidingly mounted therein, detent 80 15 members in the last-named tubular casing adapted to engage with the notches in the latches when magnetically energized, magnetic coils mounted in the tubular casing and encircling the sliding latches, said elec- 85 20 tro-magnetic coils being connected to certain of the metal fabric strips, and springs serving to operate the roller to wind the curtain when the latches are released. 90 25 5. In a fireproof window curtain, the combination with a porcelain housing and hangers, of a porcelain shade roller mounted in the hangers, an asbestos fabric shade fixed to the roller, and strips of woven wire fabric secured to one side of the asbestos 95 30 fabric to reinforce the same. 35 6. In a fireproof window curtain, the combination with a non-conductive housing and hangers, of a non-conductive roller mounted in the hangers, electric current terminals 100 40 within the roller, an asbestos fabric curtain shade fixed to the roller, strips of woven wire fabric secured to one side of the asbestos fabric and disposed longitudinally upon the shade, and means for forming a continuous contact between the electric terminals 105 45 and the wire fabric strips. 45 7. In a window curtain, the combination with a non-conductive housing and hangers, of a non-conductive roller journaled in the 110 50 hangers, springs having their inner extremity connected to the roller and their outer extremity connected to the housing and serving to turn the roller in one direction, electric terminals within the roller, an asbestos shade having one extremity fixed to the roller, strips of woven wire fabric 115 55 fixed to one side of the asbestos shade and disposed longitudinally thereon, a ratchet wheel mounted on one end of the roller, a pawl serving to prevent rotation of the 120 60 roller in one direction, means for releasing the pawl, a spring to hold the pawl in engagement with the ratchet wheel, a solenoid beneath the pawl, a plunger actuated 125 65 by the solenoid and serving to lock the pawl in operative engagement with the ratchet wheel when the solenoid is energized, non-rotative bars within the roller and connected to the electric terminals, contact rings mounted within the roller and connected to the wire fabric strips, brushes on the non-rotative bars and in contact with said rings, means for energizing the solenoid and wire fabric strips simultaneously, a switch controlling the circuit terminals and solenoid, 70 75 notched rack members fixed to the window casing, a non-conductive tubular member in the free extremity of the shade, latch members sliding therein and adapted to engage with the notched rack members on the window casing, magnetic coils disposed in the tubular member and encircling the latch members, detent members disposed in the tubular member and engaging with notches in the latch members when magnetically influenced by the latch members, means whereby the magnetic coils are energized conjunctively with the fabric strips, a spring interposed between the inner ends of the latch members and serving to maintain 80 85 them in engagement with the notched rack members when the detent members are in disengaged position, and handles projecting angularly from the inner ends of the latch members for manually disengaging them 90 95 from said notched rack members when the electric switch is in inoperative position. 8. In a window curtain, a roller consisting of two sections secured together and forming a hollow shaft, a fabric shade 100 clamped between the two sections, contact rings disposed within the shaft, insulating ring elements between the contact rings, wire fabric strips disposed on one side of the fabric shade, each strip being connected 105 to a contact ring, non-rotative bars disposed within the hollow shaft, brushes thereon and in engagement with the contact rings, electric terminals secured to said non-rotative bars and passing without the hollow 110 115 shaft, and a switch to control the terminals disposed without the shaft. 9. In a window curtain, a housing, supporting brackets thereon, a roller journaled in the brackets, spiral springs adjacent to 110 115 the brackets and having the inner end connected to the roller and their outer extremities connected to the housing and serving to turn the roller in one direction, a fabric shade fixed to the roller, means for electrically energizing the shade, a ratchet on the roller, a pawl in engagement with the ratchet and operating against the tension of the springs, a spring to actuate the pawl, means for manually releasing the pawl, and 120 125 means for locking the pawl in operative position when the curtain is energized.

In testimony whereof, I hereunto affix my signature the 12th day of August, 1920.

CLARENCE R. MAXWELL.
